UNITED STATES PATENT OFFICE.

PAUL SCHUYLER VAN BLOEM, OF HEMPSTEAD, NEW YORK, ASSIGNOR TO VIKING PRODUCTS CORPORATION, OF NEW YORK, N. Y., A CORPORATION OF NEW YORK.

ELEVATOR SIGNAL.

Application filed February 26, 1925. Serial No. 11,798.

To all whom it may concern:

Be it known that I, PAUL SCHUYLER VAN BLOEM, a citizen of the United States, and resident of Hempstead, in the county of 5 Nassau and State of New York, have invented certain new and useful Improvements in Elevator Signals, of which the following is a specification.

This invention relates to signals for indicating the approach of an elevator car and the direction of its travel.

An object of the invention is to provide an elevator signal of simple form which when unilluminated will be inconspicuous but 15 which when illuminated upon the approach of an elevator car will be rendered very conspicuous and will distinctly indicate the direction of travel of the car.

A further object is the provision of a signal lens in the form of a cover adapted to 20 substantially conceal a lamp. The lamp cover is placed over a signal lamp projecting from or mounted in the wall adjacent the elevator shaft and adapted to be illuminated when the elevator car approaches. The cover bears a direction indicating character which when unilluminated by the lamp is indistinct or entirely invisible but which 25 when the lamp is illuminated by the approach of a car will become distinctly visible. The cover lens is also designed to reflect light rays received from the signal lamp and direct them rearwardly upon the wall back of the signal in order to surround 30 the signal with a halo. This increases the conspicuousness of the signal and calls attention to the approach of the car.

In the drawings:

Fig. 1 is a front view of the signal lens;

Fig. 2 a sectional view showing the lens mounted over the signal lamp;

Fig. 3 a front view upon a reduced scale of a differently shaped signal lens; and

Fig. 4 a sectional view upon a reduced scale of a modified form of signal lens.

Referring to the parts by numerals, 1 represents the signal lamp which is mounted to be located in a proper relation to the signal lens, either in or on a wall 2 adjacent to an elevator shaft. The lamp 1 is normally unilluminated but is adapted to be illuminated by the closing of a circuit (not shown) by the approach of an elevator car.

A dished or substantially cup-shape glass 55 lens 3 is placed over the lamp 1 and sur-

rounds and encloses the outwardly projecting end of the lamp. The lens 3 is formed with a slightly convex, substantially vertical, front signal-bearing portion or wall 4, preferably circular in outline. The front 60 signal-bearing portion is supported by an integral, continuous, rearwardly extending, annular portion or member 5. The forward end of the supporting portion is connected to the front signal-bearing portion 65 around its edges and the rear end of said supporting portion is suitably flanged and is adapted to fit against the supporting wall or other lens supporting medium. The enclosing wall or member is preferably continuous and annular, as shown in Figs. 1 and 2. The said supporting portion may, however, be rectangular in cross section, and continuous, as indicated in Fig. 3, which illustrates a rectangular lens. The enclosing 70 member preferably diverges or enlarges rearwardly and is of material depth in order to off-set the signal-bearing member from the supporting wall and to completely enclose the projecting portion of the signal lamp 1. 75 The lens 3 is preferably formed of translucent glass of a suitable color so that when the lens is dark or unilluminated the face of the signal-bearing front portion will have a uniform color and will give no evidence 80 of bearing a signal or direction-indicating character. When, however, the lens is illuminated light rays will pass through the substantially vertical front signal-bearing portion and through the continuous enclosing and supporting, substantially horizontal side member 5. The direction indicating signal or character will be more 85 brilliantly illuminated than the surrounding portion of the signal bearing member 90 owing to the fact that it is of considerably less thickness than the main body of the said member.

The outer face of the signal-bearing front wall or portion 4 of the lens is slightly 100 roughened as at 12 to provide a light diffusing surface and the inner face of the said wall is formed with a depression 6 in the form of a direction indicating character. This character is indistinct or invisible when 105 the lamp is unilluminated. When the lamp is illuminated by the approach of a car the entire front face of the lens will become luminous and the direction indicating character will be distinctly visible owing to the re- 110

duced thickness of the wall 4 at the depression and also to the reflecting and refracting effect of the side walls of the depression. The depression is preferably of material depth in order to increase the contrast of the character with the surrounding face and cause the character to be clearly cutlined when illuminated. The side walls 13 of the depression are preferably smooth and disposed substantially at right angles to the bottom of the depression whereby they will reflect light rays from the lamp and direct them outwardly through the bottom of the depression. This concentration of the 15 light rays upon the character renders it more luminous.

The inner and outer faces 7 and 8 respectively of the portion 5 of the lens, are straight from front to rear and diverge rearwardly as shown. The side member or portion 5 is thus tapered and increases in thickness from front to rear and acts upon the light rays received from the enclosed lamp in the manner of a prism. It refracts the 25 said rays and, as they emerge through the outer face 8, causes them to be directed toward the room wall or lens support at the back of the lens. This causes the signal to be surrounded by a halo of light which greatly increases its conspicuousness and 30 calls attention to the approach of a car. The member 5 is formed upon its outer face with radiating ribs 9 which diffuse the light and add to the ornamental appearance of the signal. These ribs 9 taper in the same manner as the member 5 so that they also will refract the light rays from the lamp 1 rearwardly. At its rear edge the substantially 35 horizontal side portion or member 5 is formed with a flange 10 which extends around the lens and is adapted to abut the room wall 1. The lens is held in place upon the room wall in any suitable manner as by screws 11.

40 While I have shown and described my invention as adapted for use as an elevator signal, it obviously has other adaptations, as for instance, it might be used as a sign or for illuminating purposes of a particular character. It is also obvious that certain features of the signal structure such as the integral forming of the front and side walls and their cross sectional shape may be varied without departing from the spirit of 45 the invention. Fig. 4 illustrates a form of the invention wherein the front portion of the lamp covering is formed separately from the continuous lamp surrounding portion. The lamp surrounding portion is also shaped somewhat differently in cross section 50 from that shown in Figs. 1 and 2.

55 What I claim is:

1. A signal device comprising a cup-shaped lens formed with a vertically arranged front light-diffusing portion bearing

an indicating character, and a substantially horizontal cylindrical lamp-surrounding portion extending rearwardly from the said front portion, the inner and outer surfaces of said cylindrical portion being straight in 70 longitudinal section and diverging rearwardly and the rear end of said cylindrical portion being open, whereby the lens is adapted to enclose a lamp and the lamp-surrounding portion is adapted to refract rays 75 from the lamp and direct them rearwardly and the front portion will be luminous and surrounded with a halo of light caused by the rearwardly refracted light rays.

2. A signal device comprising a cup-shaped lens formed with a vertically arranged front light-diffusing portion bearing an indicating character, a substantially horizontal cylindrical lamp-surrounding portion extending rearwardly from the said front portion, the inner and outer surfaces of said cylindrical portion being straight in longitudinal section and diverging rearwardly and the rear end of said cylindrical portion being open, whereby the lens is adapted to enclose a lamp and the lamp-surrounding portion is adapted to refract rays from the lamp and direct them rearwardly and the front portion will be luminous and surrounded with a halo of light caused by the 85 rearwardly refracted light rays, and radially arranged longitudinally extending ribs on the exterior surface of the substantially cylindrical lamp-surrounding portion, said ribs causing a lateral diffusion of the light rays 90 as well as the rearward refraction thereof.

3. A signal device comprising a cup-shaped lens formed with a vertically arranged front concavo-convex light-diffusing portion having parallel inner and outer surfaces and bearing an indicating character on its inner face, and a substantially horizontal cylindrical lamp-surrounding portion extending rearwardly from the said front portion, the inner and outer surfaces of said cylindrical portion being straight in longitudinal section and diverging rearwardly and the rear end of said cylindrical portion being open, whereby the lens is adapted to enclose a lamp and the lamp-surrounding portion is adapted to refract rays from the lamp and direct them rearwardly and the front portion will be luminous and surrounded with a halo of light caused by the 100 rearwardly refracted light rays.

4. A signal device comprising a cup-shaped lens formed with a vertically arranged front concavo-convex light-diffusing portion having parallel inner and outer surfaces, a portion of said front wall being thinner than the main body thereof to give two degrees of illumination of said front wall, and a substantially horizontal cylindrical lamp-surrounding portion extending 105 rearwardly from the said front portion, the 110

inner and outer surfaces of said cylindrical portion being straight in longitudinal section and diverging rearwardly and the rear end of said cylindrical portion being open, 5 whereby the lens is adapted to enclose a lamp and the lamp-surrounding portion is adapted to refract rays from the lamp and direct them rearwardly and the front portion will be luminous and surrounded with a 10 halo of light caused by the rearwardly refracted light rays.

5. A signal device comprising a cup-shaped lens formed with a front light-diffusing portion bearing an indicating character 15 on its inner face, and a lamp-surrounding portion extending rearwardly from the said front portion, the inner and outer surfaces of said lamp-surrounding portion being straight in longitudinal section and 20 diverging rearwardly and the rear end of said portion being open, whereby the lens is adapted to enclose a lamp and the lamp-surrounding portion is adapted to refract rays from the lamp and direct them rearwardly and the front portion will be luminous and surrounded with a halo of light caused by the rearwardly refracted light rays.

6. A signal device comprising a cup-shaped lens formed with a front light-diffusing portion bearing an indicating character on its inner face, a lamp-surrounding portion extending rearwardly from the said front portion, the inner and outer surfaces 30 of said lamp-surrounding portion being straight in longitudinal section and diverging rearwardly and the rear end of said portion being open, whereby the lens is adapted to enclose a lamp and the lamp-surrounding portion is adapted to refract rays from the lamp and direct them rearwardly and the front portion will be luminous and surrounded with a halo of light caused by the rearwardly refracted light rays.

45 7. A signal device comprising a cup-shaped lens formed with a front concavo-convex light-diffusing portion having par-

allel inner and outer surfaces and bearing an indicating character on its inner face, and a lamp-surrounding portion extending 55 rearwardly from the said front portion, the inner and outer surfaces of said lamp-surrounding portion being straight in longitudinal section and diverging rearwardly and the rear end of said portion being open, 60 whereby the lens is adapted to enclose a lamp and the lamp-surrounding portion is adapted to refract rays from the lamp and direct them rearwardly and the front portion will be luminous and surrounded with 65 a halo of light caused by the rearwardly refracted light rays.

8. A signal device comprising a cup-shaped lens formed with a front concavo-convex light-diffusing portion having parallel inner and outer surfaces, a portion of 70 said front wall being thinner than the main body thereof to give two degrees of illumination of said front wall, and a lamp-surrounding portion extending rearwardly 75 from the said front portion, the inner and outer surfaces of said lamp-surrounding portion being straight in longitudinal section and diverging rearwardly and the rear end of said portion being open, whereby the 80 lens is adapted to enclose a lamp and the lamp-surrounding portion is adapted to refract rays from the lamp and direct them rearwardly and the front portion will be luminous and surrounded with a halo of 85 light caused by the rearwardly refracted light rays.

9. A signal device comprising a cup-shaped lens formed with a vertically arranged front light-diffusing portion, and a 90 substantially horizontal hollow annular lamp-surrounding portion, the rear end of said annular portion being open to adapt the lens to receive a lamp, the inner and outer surfaces of said annular portion being 95 constructed and arranged to refract rays from the lamp and direct them rearwardly, whereby the front portion will be luminous with diffused light rays and surrounded with a halo of light caused by the rearwardly refracted light rays.

In testimony whereof I hereunto affix my signature.

PAUL SCHUYLER VAN BLOEM.
